H. W. AND H. HARDINGE.
TELEHERMOSCOPE.
APPLICATION FILED APR. 19, 1916.

1,352,956.

Patented Sept. 14, 1920.

By their Attorneys,

Kerr, Page, Cooper & Hayward

UNITED STATES PATENT OFFICE.

HARRY W. HARDINGE AND HARLOWE HARDINGE, OF NEW YORK, N. Y.

TELEHERMOSCOPE.

1,352,956.

Specification of Letters Patent. Patented Sept. 14, 1920.

Application filed April 19, 1916. Serial No. 92,110.

To all whom it may concern:

Be it known that we, HARRY W. HARDINGE and HARLOWE HARDINGE, both citizens of the United States, residing at New York, 5 in the county and State of New York, have invented certain new and useful Improvements in Telethermoscopes, of which the following is a full, clear, and exact description.

10 This invention relates to telethermoscopes, for indicating at a distant point an abnormal or sudden rise of temperature, such as would be caused by fire in the room in which the device is located, and its object 15 is to provide an improved device for the purpose which will not deteriorate with time and which will operate with certainty when occasion arises. To this and other ends the invention consists in the novel features and combinations hereinafter described.

Three convenient and effective forms of the invention are illustrated in the accompanying drawings, in which Figure 1 shows 25 an embodiment in which the temperature-responsive devices are nested one inside the other, making a device of compact form. Fig. 2 illustrates an embodiment in which the two bulbs or chambers are arranged side by 30 side, and Fig. 3 shows another form.

In Fig. 1 two air-tight bulbs or chambers 10, 11, preferably made of glass, are sealed one inside the other, as shown, but communicate through a small curved tube 12 at 35 the bottom. Both these bulbs contain air or other gas. The inner bulb is inclosed also in an intermediate bulb 13 to prevent rapid transfer of heat from the outer bulb, and for this purpose the intermediate bulb 40 can be filled with heat-insulating material, or, preferably, may have the air exhausted from it so as to leave a partial vacuum. A small tube 14, extending through the wall of the outer bulb, serves as convenient means 45 through which the air can be pumped out or the insulating material introduced.

Sealed in a neck at the top of the inner bulb 10 is a pair of separated terminals or contacts 15, 16, which extend down into the 50 inner orifice of the tube 12. On the outside of the contacts are connected by wires 17, 18, through a source of current 19 to a suitable signaling device, as a bell 20. Sealed in a neck at the outer end of tube 12 is 55 another pair of insulated terminals or contacts, 21, 22, connected to the bell 20 and

in parallel with contacts 15, 16, by means of wires 23, 24. It will be understood that the bell or other signal is located at any desired point, remote or near. In the tube 12 is a 60 movable contact (a small body of mercury, 25) which also serves normally to close the tube against flow of air from one bulb into the other,

The operation of the system will now be 65 readily understood. A quick and abnormal rise of temperature, such as would be occasioned by fire, causes immediate heating of the outer bulb and the air therein but does not affect the air in the inner bulb to the 70 same extent, if at all, since the latter bulb is insulated by the intermediate bulb. Hence differential expansion of the two bodies of air in the two bulbs occurs, the air in the outer expanding more than that in the 75 inner, with the result that the body of mercury 25 is carried up into the left leg of tube 12, immersing the lower ends of contacts 15, 16, thereby closing the circuit and ringing the bell 20. As the air in the outer 80 bulb continues to expand, the mercury is driven higher and higher, until the air escapes past it into the inner bulb. The sustaining pressure being thus relieved, the mercury drops back into the bottom of the 85 tube or passage 12, thereby breaking the circuit through the bell and causing the latter to cease ringing. The air in the outer bulb now expands further, again driving the mercury up into the inner bulb, as before, and the cycle described is repeated at 90 quick intervals as long as the rapid rise of temperature continues. Finally the pressure in the inner bulb may become too great to permit the mercury to reach the contacts, 95 in which case the device would cease to operate. To prevent this result a small vent tube 26, closed with a plug of metal, wax, or other material which will melt at a suitably high temperature, is sealed in the upper 100 neck. Then when this temperature is reached the accumulated pressure in the inner bulb will blow the plug out, thereby relieving the pressure and permitting the device to operate again as long as the temperature continues to increase.

To obviate the necessity of driving the mercury clear up into the inner bulb to permit the lifting pressure of the air in the outer bulb to be relieved, a fine vent or relief tube 27 may be provided, leading from the inner bulb down to the tube or passage 110

12 and communicating with the latter at a point below its orifice. This tube is of too fine a bore for the mercury to enter it, and hence as soon as the bottom of the column 5 of mercury rises above the lower end of the relief tube the air is by-passed through the latter into the inner bulb and the mercury then drops back below the relief tube orifice, thereby cutting off communication between 10 the outer and inner bulbs 11 and 10 respectively. Further heating of the outer bulb then drives the mercury up again with the same result, the operation continuing as long as the rapid rise of temperature keeps 15 up.

Under normal conditions the rise of temperature resulting from the operation of the heating system of the building is slow. Before the air in the outer bulb can expand 20 with sufficient force to lift the mercury up to the contacts 15, 16, the air in the inner bulb will be heated enough to counteract the outer pressure.

The provision of contacts 21, 22 enables 25 the device to indicate abnormal fall of temperature. Thus a sudden drop of temperature will affect the outer bulb without appreciable influence on the insulated inner bulb, with the result that the pressure in 30 the latter exceeds the pressure in the former. The mercury 25 is thereby driven up into the right leg of the tube or passage 12, thus bridging the contacts 21, 22 and ringing the bell 20. When the bottom of the mercury 35 rises above the lower orifice of the relief tube 28, the bore of which is too fine for the mercury to enter, the pressure in the inner bulb is relieved, more or less, by flow of air through the relief tube, and the mercury 40 falls back. In this way the bell is sounded intermittently, as in the case of abnormally rapid rise of temperature. The relief tube 28 is not essential, but it is desirable, particularly in a device which does not have 45 falling temperature contacts 21, 22. It has been observed that the body of mercury sometimes sticks or clings in the upper part of the right leg of the passage or tube 12. If the contacts 21, 22 are provided, they are 50 thus closed and a signal given, summoning an attendant, who can put matters right; but without these contacts no signal is given and the device at times may not be so quickly responsive to sudden temperature change as 55 it is ordinarily. But with the relief tube present the pressure below the mercury is relieved and the mercury immediately drops back.

In either case, the escape of air past the 60 mercury and into the inner bulb equalizes the pressures in the two bulbs, or at least reduces the pressure in the outer bulb and increases the pressure in the inner to such an extent that the former is no longer sufficient to hold the mercury up. The latter

therefore falls, exposing the contacts and again choking the tube 12. Air now cannot flow from the outer to the inner bulb, and hence continued heating again increases the pressure in the outer bulb faster than in 70 the inner bulb. The operation described is therefore repeated. If the vent tube 27 is of fine bore, as already stated, the negative capillarity (so to speak) of the mercury, due to its high surface tension, will prevent the 75 mercury from entering the vent tube when driven up the tube 12. The vent tube is necessarily exaggerated in size in the drawing.

In the form shown in Fig. 2 the two air-tight bulbs 10^a and 11^a (the former inclosed in an insulating bulb 13^a) are arranged side by side instead of one inside the other. They are connected at the bottom by a tube or passage 12^a containing a body of mercury 85 25^a, and may have relief tubes 27^a, 28^a, and a vent tube 26^a sealed with fusible material. High temperature contacts 15^a, 16^a are shown in the insulated bulb, and low temperature contacts, not shown, may be provided in bulb 11^a. In operation the device 90 is of course similar to that illustrated in Fig. 1.

Having the bulbs sealed air-tight is an advantageous feature, since it minimizes oxidation of the mercury. Oxidation can be eliminated or made inappreciable by having the bulbs filled with an inert gas instead of air, as for example, carbon dioxid, or with gas having a reducing tendency, as for instance, carbon monoxid.

If the bulb containing the high temperature contacts is larger than the other, like bulbs 10^b and 11^b, in Fig. 3, the former need not be insulated; though insulation is an advantage, especially in making the device operate longer when once started. In this form of the device the temperature rise in the small bulb is greater and more rapid than in the large bulb, due to the smaller 110 volume of air (or other gas) in the former. Hence the pressure per unit area (say the cross sectional area of the tube or passage 12^b, containing the mercury 25^b) may be greater in the small bulb than in the larger. 115

In each of the devices illustrated, pressure equilibrium between the two bulbs can be restored at any time by inverting the device so that the mercury will run into one of the bulbs.

It is to be understood that the invention is not limited to the devices herein specifically illustrated, but can be embodied in other forms without departure from its spirit.

We claim:

1. In a device of the kind described, a pair of gas-filled chambers, one being heat-insulated, an electrical contact freely movable between the chambers, a pair of fixed 125 130

- separated contacts arranged to be electrically closed by the movable contact in its travel toward one of the chambers, and a by-pass for permitting the escape of gas 5 from one chamber to the other when the movable contact reaches a predetermined point in its travel after closing said fixed contacts, whereby rapid change of temperature will cause repeated closing of the fixed 10 contacts.
2. In a device of the kind described, a pair of sealed gas-filled chambers having a passage connecting the same at the bottom, one of the chambers being heat-insulated, 15 a pair of separated contacts, a freely movable contact in the passage, normally out of engagement with the said contacts and normally sealing the passage, and a relief passage extending from the first-mentioned passage below an orifice thereof and opening 20 into the adjacent chamber.
3. In a device of the kind described, a pair of gas-filled chambers, one being heat-insulated and provided with a vent sealed with fusible material adapted to melt and 25 permit escape of gas at a predetermined temperature above the normal, an electrical contact freely movable between the chambers, a pair of fixed separated contacts arranged to be electrically closed by the movable contact in its travel toward one of the chambers, and a by-pass for permitting the escape of gas from one chamber to the other when the movable contact reaches a predetermined point in its travel after closing 30 said fixed contacts, whereby rapid changes of temperature will cause repeated closing of the fixed contacts.

In testimony whereof we hereunto affix our signatures.

HARRY W. HARDINGE.
